FIG. 1

The dominant features of my design reside in the portions shown in full lines, the broken line showing of the handle being for illustrative purposes only.

I claim:

The ornamental design for a mop head, as shown and described.
